Application November 25, 1955, Serial No. 548,890

5 Claims. (Cl. 197—19)

This invention relates to an improved consecutive serial numbering device operable alone or in combination with a printing mechanism.

In many typewriter applications, for example, in making out payroll checks wherein the checks have to be numbered consecutively, it is somewhat of a burden to the typist to insure accurate numbering, and the advantages of an automatic consecutive serial numbering device become obvious.

Therefore, it is a first object of this invention to provide an improved consecutive serial numbering device.

It is a further object of this invention to provide an automatic consecutive serial numbering device which is operable in combination with a printing mechanism to print numerals in series.

It is a still further object of this invention to provide an improved automatic consecutive serial numbering device which will provide pulses for controlling the operation of a printing mechanism.

It is a still further object of this invention to provide an improved pattern control electrical pulse device which is operable in combination with a printing mechanism to print items in accordance with the predetermined pattern.

Other objects of the invention will be pointed out in the following description and claims and illustrated in the accompanying drawings, which disclose, by way of example, the principle of the invention and the best mode, which has been contemplated, of applying that principle.

In the drawing:

Fig. 1 is a side elevation of a solenoid controlled type bar drive mechanism in its rest position.

Fig. 2 is a side elevation of a solenoid controlled type bar drive mechanism in its active position and,

Fig. 3 is a schematic wiring diagram of the improved consecutive serial numbering device.

Briefly, this invention relates to a combined mechanism and control circuitry for selectively and automatically driving typewriter printing means into printing position.

In the illustrated embodiment, a six decimal order mechanism is provided which, when selectively operated, will cause typewriter type bars to print seriatim from 0000001 through 999999.

In accomplishing this objective, a cam lever of conventional construction 2, is provided for each type bar of a typewriter. Each cam lever is pivotally supported on a fulcrum wire 4 and carries a cam 6 which may be moved into engagement with the power roll 8 to drive the cam lever 2 counterclockwise from its rest (Fig. 1) position to its active (Fig. 2) position thereby driving a type bar 9 into printing position. The cam 6 can be moved into engagement with the power roll to initiate a type bar print stroke, either by depression of the key lever 10 acting through a trip latch 12 (as shown in U.S. Patent 2,723,740), or through the energization of a magnet unit 14, which operates via a link 16 to push on the tail of

cam 6. One magnet unit 14 with link 16 is provided for each of the numeric type bars.

The tail of the cam lever 2, in moving to printing position, rocks a ribbon lift vane 18 (common to all cam levers) which is pivotally mounted on a fulcrum wire 20. The ribbon lift vane is equipped with a tail 22, which actuates a set of contacts generally designated as 24. Actually, there is a center movable contact element 26, which at rest position, engages one contact 28 (normally closed) as shown in Fig. 1, and in its active position as shown in Fig. 2, engages the contact 30 (normally open). It will be understood that each time a type bar is driven into printing position, the ribbon vane 18 will be rocked about its pivot 20 to move the movable contact 26 from its normally closed side to its normally open side. As will be later explained, the transferring of movable contact 26 acts to trigger circuitry for sending pulses through each of six devices representing six decimal orders, every time the consecutive serial numbering device is operated.

With reference to the wiring diagram of Fig. 3, the consecutive serial numbering mechanism comprises a plurality of stepping or distributing switches such as the emitter switch 32 and interconnecting circuitry. Each of the stepping switches is provided with a plurality of radial contacts and a center sweep arm operable under control of an advance magnet. The center sweep arm is stepped one radial contact position each time its advance magnet is pulsed.

With specific reference to emitter switch 32—but applicable to all the stepping switches—each time the emitter advance magnet 34 of emitter switch 32 is energized, the center sweep arm 33 will move to the next radial contact. The center sweep arm 33 in turn, is provided with a brush 36, and accordingly, a pulse available at the brush 36 may be distributed to the radial contacts seriatim as the emitter advance magnet 34 is pulsed. Since the theory of operation is based upon the fact of sending a pulse through each of six decimal orders for each operation of the consecutive serial number device, six of the radial contacts of emitter switch 32 are connected to a bank of six stepping or distributing switches 38—one for each decimal order—as follows:

Decimal order:	Distributing switch
100,000	38-100T
10,000	38-10T
1,000	38-1T
100	38-100
10	38-10
1	38-1

Each distributing switch 38 has a center brush 40, a sweep arm 42 and ten stepped radial contacts. Each radial contact is connected to one of the magnet units 14 of the numeric type bars. That is, the zero radial contact of each of the distributing switches 38 is connected in parallel to the magnet unit 14 for the zero type bar; the 1 radial contact of each of the distributing switches 38 is connected in parallel to the magnet unit 14 for the numeral one type bar, etc.

The brush 40 of each of the distributing switches 38 is connected to one of the radial contacts of the emitter switch 32 in the following order:

Brush:	Emitter contact point
40-100T to	32-1
40-10T to	32-2
40-1T to	32-3
40-100 to	32-4
40-10 to	32-5
40-1 to	32-6

With this arrangement, a pulse through the 32-1 radial contact of emitter switch 32 will go through a conductor

to the brush 40-100T, through the sweep arm 42-100T, through one of its radial contact points to its associated magnet unit 14. Then when arm 33 of emitter switch 32 advances to the second radial contact 32-2, a pulse is available to brush 40-10T, through its sweep arm 42-10T, through the engaged radial contact to the associated magnet unit 14. This operation is continued through the six orders represented by the six distributing switches 38.

For each operation of the consecutive serial numbering device, it is necessary to step the emitter switch 32 (by successively energizing its advance magnet 34) through a complete cycle; that is, from a rest position through all the radial contacts 32-1 through 32-6 so as to send a pulse through each of the stepping switches 38 and back to rest position. To accomplish this (with reference to wiring diagram of Fig. 3), a pulse is available from line 44 to a start key 46, which in turn, has a normally open contact 48, and a normally closed contact 50 so that depression of the start key directs a pulse from line 44 through normally open (now closed) contact 48 through a normally closed contact point 54-1 to energize relay 52. A parallel circuit is provided through rectifier 53 to emitter advance magnet 34. Relay 52 has a normally open contact point 52-1 in series with a relay 54, which is a latch type relay, that will stay latched when energized until it is unlatched by energizing an unlatch magnet 56. Accordingly, when relay 52 is picked up, a pulse is available through contact 52-1 normally open (now closed) to pick up relay 54 and hold it latched. Relay 54 has a normally closed contact point 54-1 in series with relay 52 and with the parallel circuit through rectifier 53 to emitter advance magnet 34; therefore while relay 54 is latched, relay 52 cannot be energized again by again depressing the start key 46; nor can emitter advance magnet 34 be pulsed through rectifier 53. Relay 54 further has a normally open contact point 54-2 in series with brush 36 of stepping relay 32; 54-3 in series with emitter advance magnet 34; and normally closed contact points 54-4 in series with a conductor 51.

When a type bar is in rest position—and assuming switch 46 has returned to its normal position after being actuated to energize the relay 54, a pulse is available from line 44, through normally closed contact 50, through line 49, through normally closed ribbon vane contact 28, through normally open—now closed—contact 54-2, through brush 36 of emitter switch 32, through movable contact arm 33 to a radial contact. When a type bar moves to print position, this circuit is broken by the opening of contact 28, and a circuit is established from line 44, through normally open, now closed, contacts 30 and contact 54-3 to emitter advance magnet 34 thereby energizing magnet 34 to advance sweep arm 33 to the next radial contact of emitter stepping switch 32. With this circuitry, it is apparent that the emitter stepping switch 32 will be stepped in sequence through all its radial contact points, up to radial contact point number 6, each time the emitter advance magnet 34 is pulsed as a result of a type bar print stroke. It is also apparent that since the radial contact points of the emitter stepping switch 32 are connected respectively to the different orders covered by the stepping switches 38, that a pulse will be available through the bank of distributing switches 38, seriatim, from 100,000 order 38-100T down to units order 38-1.

The emitter stepping switch 32 is shown as having eight radial contact positions, but it could have any number more than the number of distributing switches in bank of switches 38. For example, it could have ten positions as have the other stepping switches 38. For all radial contact positions not directly connected to the distributing stepping switches 38, a pulse is available from that respective contact point directly to the emitter advance magnet 34 to step the emitter one further step. When the contact arm 33 of emitter stepping re-

lay 32 is on the number 8 contact point as shown in Fig. 3 (while type bar is in rest position), then a pulse is available through contact 28 normally closed, contact 54-2 normally open now closed, through brush 36, contact arm 33, radial contact 32-8 to unlatching relay 56, thereby dropping out magnet 54 to interrupt the consecutive serial numbering circuit. The movable contact arm 33 will rest on the number 8 radial contact point until a new cycle is initiated. In one cycle then, contact arm 33 moves from contact 32-8 through all other radial contacts of emitter switch 32 in sequence back to contact 32-8. Incidentally, it is apparent that the pulse through radial contact 32-7 could be sent to a magnet 35 via switch 37 which could control the carriage return operation or some other function of the typewriter, thereby returning the carriage to a starting position after the consecutive serial numbering device has gone through a cycle.

With reference to the bank of stepping switches 38, each one is equipped with a nines carry stepping switch 58 and its individual advance magnet 60. Each of the stepping switches 38 and 58 of the same order has its movable contact arm 42, 62 respectively in alignment on the same shaft indicated by the dotted lines 64. That is, the advance magnet 60-1 steps shaft 64-1 and hence contact arms 42, 62 of switches 38-1 and 58-1 one radial contact position at a time.

A circuit in parallel with advance magnet 60-1 is provided to brush 66 of nines carry switch 58-1. Then, when the units order shaft 64-1 has been advanced to bring contact arm 62 of switch 58-1 into engagement with radial contact 9 of stepping switch 58-1, the next pulse to advance magnet 60-1 also provides a pulse through brush 66 and contact 9 of switch 58-1 to energize advance magnet 60-10 thereby moving contact arms 42 and 62 of switches 38-10 and 58-10 to their 1 radial contact positions, respectively, while the arms 42 and 62 of the switches 38-1 and 58-1 move to their 0 radial positions. Therefore, the magnets 60-10, 60-100 etc., that control the advance of the stepping switches 38, 58 in other than the units orders, are pulsed only each time the 9 radial points of all previous orders have been reached and a next pulse is received. To reiterate, when a pulse is available to advance magnet 60-1 which in turn causes one step of both the stepping switches 38-1 and nines carry switch 58-1, the nines carry switch 58-1 must have been advanced nine positions before a pulse is available to the tens order advance magnet 60-10, and nines carry switch 58-10 must be advanced from 0 through 9 before a pulse is available to the hundreds carry magnet 60-100 etc.

In operating the consecutive serial numbering device—assuming all switches are in their zero radial contact positions, the start key 46 is depressed so that a pulse is available from the line 44 through the normally open contact 48 to energize relay 52 and emitter advance magnet 34. The latter advances the stepping relay 32 from the number 8 to the number 1 radial contact point. The relay 52 closes contact 52-1 thereby energizing and latching relay 54. Prior to relays 52 and 54 picking up, the pulse through the normally open contact 48 (now closed) passes through line 51 and through normally closed contact point 54-4 both to the units advance magnet 60-1, pulsing that relay to advance it one unit and to brush 66-1, and contact arm 62-1 of the nines carry switch 58-1. Stepping switch 38-1 is advanced to its 1 radial contact point, due to energizing 60-1, and switch 58-1 is advanced to its 1 contact point. The pulse to the switch 58-1 is superfluous since the arm 62 of switch 58-1 is connected with the dead number 1 radial contact. Then when the key 46 is released and a pulse is available through the normally closed contact 50, through line 49 to the normally closed ribbon vane operating contact 28 and through the contact 54-2 (now closed) to the brush 36 of emitter stepping switch 32 which is now on radial contact number 1. The pulse from contact 32-1 goes to the brush 40 and contact arm

42 of order distributing switch 38-100T which will be on the 0 position, then to the magnet unit 14, for the zero type bar. This type bar will move to printing position and in doing so will open the contacts 28 controlled by the ribbon lift vane and close contact 30, whereupon a pulse is available from line 44 through contact 30, through a contact 54-3 now closed to the emitter advance magnet 34, stepping the emitter stepping switch 32 to the number 2 radial contact position. The type bar will drop back to its rest position, and in doing so will close the contact 28, whereupon a pulse is again available through the emitter stepping switch 32, this time through contact 32-2 to the order switch 38-10T which is at zero position and accordingly energizes the magnet unit 14 to the zero type bar again. This is repeated down to the units order switch 38-1 which is on the 1 radial contact point and the pulse to that one will energize the magnet unit 14 for the numeral 1 type bar and accordingly, numeral 1 will be printed. As that type bar restores to its rest position, the pulse through the vane contact 28 and through contact 54-2 will be available through radial contact point 32-7 of the emitter stepping switch 32 which will pulse the emitter advance magnet 34, moving it to the contact 32-8 position, but the contact 28 will not be broken, since there was not type bar print stroke. A pulse will then be available through the number 8 radial contact point of the emitter stepping switch 32 which will pulse the unlatch magnet 56 to open the latch relay 54 thereby breaking the circuit to the consecutive serial numbering device until switch 46 is again operated.

While there have been shown and described and pointed out the fundamental novel features of the invention as applied to a preferred embodiment, it will be understood that various omissions and substitutions and changes in the form and details of the device illustrated and in its operation may be made by those skilled in the art without departing from the spirit of the invention. It is the intention therefore, to be limited only as indicated by the scope of the following claims.

What is claimed is:

1. In a typewriter having a plurality of type bars with individually controlled power means for driving the same into printing position and solenoid means acting when energized to initiate a type bar print stroke, a device for energizing said solenoid means in accordance with a predetermined pattern comprising a plurality of multi-contact order distributing switches assigned one to each pattern order, each of said switches having a sweep contact arm, circuit means interconnecting common contacts of each of said order switches to said solenoids, emitter switch means for sending a pulse through each order of said order switches seriatim for energizing said solenoids in accordance with the respective settings of said order distributing switches, and means controlling the operation of said distributing switches to channel pulses to said solenoids selectively, said controlling means comprising a carry switch associated with each of said distributing switches and having a 9 contact, a sweep contact arm associated with each of said carry switches and movable synchronously with the sweep contact arm of the distributing switch associated therewith, an advancing solenoid associated with each of said distributing switches and the corresponding carry switch for advancing said switches when said associated advancing solenoid is energized, and means for energizing the units order advancing solenoid and for energizing successive order advancing solenoids when said sweep contact arms of all lower order carry switches stand on 9.

2. In a typewriter having a plurality of type bars with individually controlled power means for driving said type bars into printing position and solenoid means for triggering said power means, a consecutive serial numbering device for energizing said solenoid means seriatim comprising a plurality of multi-contact order distributing switches assigned one to each decimal order, a sweep

contact arm for each of said decimal order distributing switches, means stepping said sweep contact arms of said decimal order distributing switches in numeric succession, said stepping means comprising a carry switch associated with each of said distributing switches and having a 9 contact, a sweep contact arm associated with each of said carry switches and movable synchronously with the sweep contact arm of the corresponding distributing switch, an advancing solenoid associated with each of said order distributing switches and the corresponding carry switch for advancing said switches when said associated advancing solenoid is energized, and means for energizing a units order advancing solenoid and for energizing successive order advancing solenoids when said sweep contact arms of all lower order carry switches stand on 9, said last mentioned means comprising circuit means connecting the 9 contact of each carry switch in branch circuits to the advancing solenoid and the contact arm for the next higher order carry switch.

20 3. In a typewriter having a plurality of numeric type bars with individually controlled power means for driving said type bars into printing position and solenoid means for operating said power means to initiate a numeric type bar print stroke, a consecutive serial numbering device for energizing said solenoid means seriatim comprising a plurality of order distributing switches assigned one to each decimal order, a contact on each of said decimal order distributing switches representing the 0 through 9 units, a sweep contact arm engageable with said 0 through 9 contacts one at a time, conductor means interconnecting common contacts on each of said decimal order distributing switches with said solenoids, emitter switching means for energizing said sweep contact arm of each of said decimal order distributing switches one at a time thereby energizing a solenoid to initiate a type bar print stroke, and means for advancing said decimal order distributing switches seriatim, said advancing means comprising a carry switch associated with each of said distributing switches and having a 9 contact, a sweep contact arm associated with each of said carry switches and movable synchronously with the corresponding first sweep contact arm, an advancing solenoid associated with each of said distributing switches and the corresponding carry switch for advancing said switches when said associated advancing solenoid is energized, and means for energizing a units order advancing solenoid and for energizing successive order advancing solenoids when said sweep contact arms of all lower order carry switches stand on 9.

40 4. A consecutive numbering device comprising in combination a plurality of type bars, a solenoid associated with each of said type bars, solenoid actuated means for driving said type bars into printing position, a plurality of multi-contact distributing switches assigned one to each decimal order, conductor means connecting common contacts of each of said decimal order distributing switches to said type bar solenoids respectively, a sweep arm for each of said distributing switches, means for advancing said sweep arms of said decimal order distributing switches in numeric series, an emitter switch having individual contacts electrically connected respectively to said decimal order distributing switches whereby pulses may be sent through the latter to energize said solenoids consecutively, and means responsive to the resultant type bar print stroke for advancing said emitter switch for contact with the next decimal order distributing switch, said means for advancing said sweep arms comprising a carry switch associated with each of said distributing switches and having a 9 contact, a sweep contact arm associated with each of said carry switches and movable synchronously with the sweep contact arm of the corresponding distributing switch, an advancing solenoid associated with each of said distributing switches and the corresponding carry switch for advancing said switches when said associated advancing solenoid is energized, and means for energizing said advancing solenoid in units order posi-

tion, and for energizing successive order advancing solenoids when said sweep contact arms of all lower order carry switches stand on 9.

5. A typewriter comprising in combination a plurality of type bars, individually controlled power driven means for driving the same into printing position, electrical means assigned to each individual power means for triggering a type bar print stroke, and a device for selectively energizing said electrical means in accordance with a predetermined pattern comprising a plurality of multi-contact pattern distributing switches—one for each order of said predetermined pattern, conductor means interconnecting common contacts of said pattern switches with said electrical means, and multi-contact emitter means for sending seriatim a pulse through each order of said pattern 15

10
15

switches to energize selectively said electrical means comprising an advance relay acting when energized to advance the emitter means one contact position, conductor means interconnecting said emitter contacts with one order of said pattern switches respectively, and means responsive to a type bar reaching print position for energizing said advancing relay.
